FISH HOOK REMOVER

Anthony Enagureto, 7829 Hamilton Ave.,
Pittsburgh, Pa. 15208

Filed July 6, 1972, Ser. No. 269,290

Term of patent 14 years

Int. Cl. D22—05

U.S. Cl. D22—31

Fig.1.

Fig.2.

Fig.3.

FIG. 1 is a top, perspective view of a fish hook remover, shown in the initial position and embodying my new design;

FIG. 2 is a similar view shown in the operated position; and

FIG. 3 is a bottom, perspective view thereof shown in FIG. 1.

I claim:

The ornamental design for a fish hook remover, substantially as shown and described.
